UNITED STATES PATENT OFFICE.

EDWARD T. SCHOONMAKER, OF FORDHAM, NEW YORK, ASSIGNOR TO PEER-LESS MANUFACTURING COMPANY, OF LOUISVILLE, KENTUCKY, A CORPORATION OF DELAWARE.

DESIGN FOR A FIREPLACE-FRONT.

SPECIFICATION forming part of Design No. 35,384, dated December 3, 1901.

Application filed October 19, 1901. Serial No. 79,310. Term of patent 3½ years.

To all whom it may concern.

Be it known that I, EDWARD T. SCHOON-MAKER, a citizen of the United States, residing at Fordham, in the county of New York 5 and State of New York, have invented and produced a certain new and original Design for Fireplace-Fronts, (Case B,) of which the following is a full, clear, and exact description.

10 This invention relates to what is known on the market as a "fireplace-front."

In the accompanying drawing, forming part of this specification, the invention is illustrated in front elevation.

15 As shown in the drawing, the leading or material feature of my design consists of a frame the sides of which are provided in high relief with bulb-like foliation, having a central stem projecting above it with lateral 20 branches, and a central oval figure having a border of beads and a center representing a fleur-de-lis, above which is a laterally-extending ribbon and a conventionalized fan-like trefoil. The cross-piece has a center-piece 25 composed of a conventionalized ancient gallery surmounted by eagles' heads and flanked by leafy branches. The corners are orna-

mented with suspended casket-like figures with surrounding flowing ribbons or streamers. The molding is composed of reeds alternating with couplets of beads. The center or summer-front has a molding of reeds bound with ribbons with indented corners in which are stars surrounded by circles of beads, and within this molding is a reproduction of a well-known work of art. The molding in this summer-front or center-piece is further ornamented on each side by intertwined leafy branches and ribbons or streamers. The background of the sides and so 40 much of the center-piece as contains the intertwined leafy branches is stippled or has a granular appearance.

Having thus described my invention, what I claim as new, and desire to secure by Letters 45 Patent, is—

The design for a fireplace-front, substantially as shown and described.

In testimony whereof I have hereunto set my hand this 14th day of October, A. D. 1901. 50

EDWARD T. SCHOONMAKER.
